GAME DEVICE

Filed April 7, 1924

Inventor
Leslie M. Parker

by Parker & Carter
Attorneys.

UNITED STATES PATENT OFFICE.

LESLIE MONROE PARKER, OF CHICAGO, ILLINOIS.

GAME DEVICE.

Application filed April 7, 1924. Serial No. 704,574.

To all whom it may concern:

Be it known that I, LESLIE MONROE PARKER, a citizen of the United States, and resident of Chicago, in the county of 5 Cook and State of Illinois, have invented certain new and useful Improvements in Game Devices, for which the following is a full, concise, and exact description.

This invention relates to a game device, 10 and particularly to a device adapted for use both during the playing of a game and while the game is not being played. It thus serves as an accessory device for playing the game and as a storage device or 15 receptacle for the pieces with which the game is played. It has for one object to provide a retaining and displaying rack upon which the game pieces may be positioned and within which the counters may 20 be held, and which may also be used as a storage device for both the game pieces and the counters and other game parts when the game is not being played. Another object is to provide means for associating together 25 a plurality of such racks to form a storage receptacle. Another object is to provide means for fastening together a plurality of such racks. Other objects will appear from time to time throughout the specification 30 and claims.

My invention is illustrated more or less diagrammatically in the accompanying drawing, wherein:

Figure 1 is a plan view of two racks or 35 trays slightly separated;

Figure 2 is a cross section taken on line 2-2 of Figure 1;

Figure 3 is an end elevation of a plurality 40 of racks assembled in one form;

Figure 4 is a cross section on an enlarged scale showing the racks assembled as in 45 Figure 3.

Like parts are designated by like characters throughout.

45 A is a rack or tray. It is formed as shown with a closed-sided pocket or cavity A¹ which is formed of a plurality of cavities made by means of partitions A². It is provided with an open-sided pocket B. 50 This pocket is preferably formed in the shape of an open-sided trough with sides inclined to horizontal, and serves when the game is being played as a receptacle within which the game pieces may be held and inclined so as to be visible only to the player.

In the form illustrated herewith each of the racks is provided preferably at its center and on the same side as the open-sided pocket or trough with a half-rounded portion C. When the portions of the rack are 60 fastened together as shown in Figure 4, the half-rounded portions C are in register with each other and thus form a round perforation through the center of the resulting double drawer or tray.

65 Two of the racks are preferably provided in their under side with a cavity C¹ which may be provided adjacent its outer edge with a deepened portion C². This cavity C¹ C² may be of any shape but I prefer 70 to have it angular.

I have provided along one side of each of the racks an engaging device which may be of any suitable form. The form illustrated herewith is formed of a spring engaging assembly. Each of said assemblies includes a penetrating and a surrounding part. I prefer to put each of the penetrating parts D, D on one member and to put 75 the surrounding parts D¹, D¹ on the other member. The details of these parts are not shown as they form no part of the present invention. It is sufficient to use any one of many well known types of snap fasteners 80 for this purpose. By means of the use of 85 these, two trays or racks may be assembled and removably fastened together so as to form in effect a double tray or drawer.

E is a joining and fastening bolt. It is 90 preferably provided with a flat head E¹ which has in its outer edges upturned portions E². The head E¹ lies generally within the cavity C in the bottom of the racks and the upturned portions E² lie within 95 the deepened portion C² of the cavity C¹. The bolt E is threaded at its upper end at E³ and is adapted to receive a threaded handle E⁴.

F is a cover plate adapted to extend over 100 a pair of racks and to serve as a cover for the upper pair. It is perforated to receive the bolt E and is preferably provided around the perforation with a wearing part F¹ against which the handle E⁴ is seated when the parts are drawn together in the closed position shown in Figures 3 and 4.

In order to assure proper seating and 105 register of the racks when they are assembled as shown in Figures 4 and 3, the outer wall portion of each rack is preferably 110

provided with an inwardly sloping bevelled edge G, and some or all of the racks are provided on their bottom with a corresponding bevelled portion G¹. This bevelled portion may be omitted from the bottom set of racks or it may be included. The cover plate F is correspondingly bevelled on its under side so as to fit into and register with the upper pair of racks. By means 10 of these co-operating bevelled faces the racks positively register and it is impossible to assemble them in improper order. When drawn together by means of the central bolt they are firmly held together.

15 The use and operation of my invention are as follows:

When it is desired to play the game, the unit racks are separated and the counting devices may be stored within the closed 20 sided pockets for the use of the player. The game pieces which the player holds are placed in an inclined position on the open-sided facing the player. When the parts are to be put away, the pairs of racks are 25 snapped together or otherwise separably fastened together in the position shown particularly in Fig. 2, and in that position the game pieces are preferably placed in the closed-sided pocket and the counters and 30 other game devices used are placed in the additionally formed long central trough. This trough constitutes a closed sided-pocket formed of a pair of open-sided pockets in a single rack.

35 After the racks are fastened together, the bottom pair is placed over the bolt so that the bevel extends upwardly through the perforation. The next pair is placed upon the first pair also having the bolt pass through 40 it and by reason of the bevel arrangement the parts are readily and positively centered and register with respect to each other. The cover plate is then put on top of the 45 pile, the handle is screwed in position on the pile and the parts are all held together and they form thus in effect a box containing the racks necessary for use when the game is being played and all of the game pieces.

50 I have shown four racks. Two could be used or any number could be used. However, as the game for which this device is particularly adapted is played at present, four racks will be used.

55 While I have shown one method of fastening the four racks together, I do not wish to be limited to it. Many other methods of fastening the racks together might be used. The bolt need not be used. The handle need 60 not come on the top of the pile of racks. The racks might be inserted as drawers in a box provided for them in the manner described and shown in my pending application Serial Number 682,388 filed December 24, 1923, 65 and many other changes might be made in

size, shape and arrangement of parts without departing materially from the spirit of my invention.

I claim:

1. A game device including in combination a plurality of unit rack members, means for separably joining pairs of such unit rack members in their normal upright position, and means for separably assembling together a plurality of such pairs of members. 75

2. As a new article of manufacture a game device comprising racks adapted for use during the playing of a game, means for separably joining together pairs of such racks to form storage devices for the game pieces, and means for separably assembling together a plurality of said composite storage devices. 80

3. A game device including in combination a plurality of unit rack members, means for separably joining pairs of such unit rack members, and means for separably securing together a plurality of such pairs of members, in combination with a cover plate. 85

4. As a new article of manufacture a game device comprising racks adapted for use during the playing of a game, means for separably joining together pairs of such racks to form one storage device for the game pieces, and means for separably assembling together a plurality of said composite storage devices so that each upper member forms a cover for the one beneath it. 95

5. As a new article of manufacture a game device comprising racks adapted for use during the playing of a game, means for separably joining together pairs of such racks to form a storage device for the game pieces, and means for separably assembling together a plurality of said composite storage devices so that each upper member forms a cover for the one beneath it, in combination with a cover plate adapted to serve as a cover for the uppermost storage device. 100

6. A game device including in combination a plurality of unit racks, each of said racks having a closed-sided pocket and an open-sided pocket, means for separably joining pairs of such rack members, and means for separably assembling together a plurality of such pairs of members. 115

7. A game device including in combination a plurality of unit rack members, each of said members having a closed-sided pocket and an open-sided pocket, means for separably joining pairs of such rack members together whereby the open-sided pockets are brought together to form an additional closed-sided pocket, and means for separably assembling together a plurality of such pairs of members. 120

8. A game device including in combination a plurality of unit rack members, each of said members having a closed-sided pocket 125

130

and an open-sided pocket, means for separably joining pairs of such rack members together whereby the open-sided pockets are brought together to form an additional 5 closed-sided pocket, and means for separably securing together a plurality of such pairs of members one on top of the other.

9. A game device including in combination a plurality of unit rack members, each 10 of said members having a closed-sided pocket and an open-sided pocket, means for separably joining pairs of such rack members together whereby the open-sided pockets are brought together to form an additional 15 closed-sided pocket, and means for separably securing together a plurality of such pairs of members one on top of the other, and a cover plate adapted to rest upon the uppermost of such pairs of members.

20 10. A game device including in combination a plurality of unit rack members, each of said members having a closed-sided pocket and an open-sided pocket, means for separably joining pairs of such rack members together whereby the open-sided pockets are brought together to form an additional 25 closed-sided pocket, and means for separably securing together a plurality of such

pairs of members one on top of the other, and a bolt adapted to extend from top to 30 bottom of the assembled pairs of members, in combination with a handle adapted to draw and hold the members together upon the bolt and to serve as a carrying handle for the assembled rack members. 35

11. A game device including in combination a plurality of unit rack members, each of said members having a closed-sided pocket and an open-sided pocket, means for separably joining pairs of such rack members 40 together whereby the open-sided pockets are brought together to form an additional closed-sided pocket, and means for separably securing together a plurality of such pairs of members one on top of the other 45 and a cover plate adapted to rest upon the uppermost of such pairs of members, and a bolt adapted to extend from top to bottom of the assembled pairs of members, in combination with a handle adapted to draw and 50 hold the members together upon the bolt and to serve as a carrying handle for the assembled rack members.

Signed at Chicago, county of Cook and State of Illinois, this 4th day of April 1924.

LESLIE MONROE PARKER.
